UNITED STATES PATENT OFFICE.

JAMES STORIE, OF EDINBURGH, SCOTLAND.

APPARATUS FOR RAISING AND LOWERING SHIPS' BOATS.

1,271,237.

Specification of Letters Patent.

Patented July 2, 1918.

Application filed June 20, 1916. Serial No. 104,741.

To all whom it may concern:

Be it known that I, JAMES STORIE, a subject of the King of the United Kingdom of Great Britain and Ireland, and resident of 2
5 Rossie Place, Edinburgh, Scotland, have invented certain new and useful Improvements Relating to Apparatus for Raising and Lowering Ships' Boats, of which the following is a specification.

10 This invention relates to apparatus for raising and lowering ships' boats and has for its object to provide an improved apparatus of simple construction which among other advantages will render it possible to
15 launch boats from either side or both sides of a ship which by accident or otherwise has been caused to have a serious list; to launch boats safely in rough weather, or while the ship is rolling; and also while the ship is
20 moving at a moderate speed.

My invention relates to that kind of apparatus which comprises a cradle or the like adapted to support a boat by pivotal or other supports at each end and arms adapted to support the said cradle, the said arms being substantially vertically disposed down the sides of the ship and pivotally mounted at their lower ends and means whereby the arms may be turned in a vertical plane about 25 their lower ends. In arrangements of this class the arrangement is such that when it is required to launch a boat the arms are allowed to swing down, pivoting about their lower ends so that the cradle which is supported
30 between the upper ends is swung wide of the side of the ship until the boat carried thereon reaches the water, when it automatically floats free of the cradle.

35 The use of vertically disposed arms pivoted at their lower ends and carrying boats at their upper ends for raising and lowering ships' boats presents two difficulties, the first of which arises from the fact that the slightest backward list of the vessel will
40 either put the arms out of action or necessitate the use of power in turning them downwardly so as to launch the boat.

45 This difficulty has been overcome by the apparatus which I have invented, by the
50 employment of an arrangement of links at the lower parts of the arms which allows the upper end of each arm to descend in a downwardly inclined line which is substan-

tially straight whereby every part of the course taken by the boat has a considerable 55 downward inclination. It will be evident that when this condition obtains the weight of the boat and of the arms themselves will cause the boat to descend when the arms are unlocked even when there is a backward 60 list of the vessel which is fitted with the apparatus.

In the example of my apparatus which is illustrated the design is such that the arms will descend as soon as they are unlocked 65 while the vessel carrying the apparatus is in any position up to a backward list of 35°. By modifying the proportions of the link work effectiveness can be obtained for even a greater degree of inclination. If required 70 the link work can be so designed that the descending path taken by the boat would be substantially vertical for some distance, say as far as the main deck, and subsequently downwardly inclined away from the ship's 75 side.

The other obstacle in connection with the use of pivoted arms of the kind mentioned for raising and lowering ships' boats is the difficulty of withdrawing the arms or supporting means from the boat instantly after the boat has reached the water. It is of extreme importance that this should be done as the proximity of any rigid apparatus to a boat which is floating would be highly dangerous in rough weather.

This difficulty is overcome by the use of the present apparatus in which after the boat has floated the arms and supporting means immediately and quickly sink well 80 below the surface of the water until they again take up a position near the ship's side. If necessary the arms or the supporting means may be specially weighted in order to insure that this action will take place.

90 The accompanying drawings illustrate by way of example one form of apparatus constructed in accordance with the present invention.

Figure 1 is a view in side elevation.

Fig. 2 is an end view showing the apparatus in three different positions.

Fig. 3 is a diagram in which is shown the path taken by the boat when there is a backward list of the vessel carrying the apparatus.

In the construction illustrated each boat is carried in a cradle which comprises a cranked beam *a* which passes under the keel of the boat *b* and is turned upwardly at each 5 end *a*¹. The ends *a*¹ of the beam *a* are each pivoted to one of the main supporting arms *c*. The beam *a* is provided with chocks or other means *a*² fitted approximately to the shape of the under side of the boat *b* and 10 adapted not only to support it but to enable it automatically to float freely upon reaching the water.

The two supporting arms *c* each consists of a beam extending down the ship's side 15 and the upper end of which is bent backward at *c*¹ allowing the boat *b* to hang over the deck as shown in Fig. 2. Each arm *c* carries a bracket *c*² some little distance from its upper end and the two brackets *c*² are 20 joined by the beam *c*³. The rope or chain is connected to the middle of the beam *c*³ and the said rope or chain extends over a winch *d* by which the apparatus is let down and drawn up.

25 Any suitable form of winch may be employed but I prefer to use one of the kind having two drums on to one of which is wound the rope connected to the beam *c*³, the other drum being used to raise the boat 30 from the water by one of the alternative methods hereinafter described. The winch also comprises suitable braking means and also a locking clutch by which the winch can be locked in any desired position, the arrangement being such that when the apparatus 35 has been raised the winch is locked by the clutch, and when it is desired to lower the apparatus the clutch is released and the brake is applied to the winch so that the apparatus descends at a speed controlled by 40 the brake of the winch entirely by reason of its own weight.

Each arm *c* is provided with a pin or roller *c*⁴ which is adapted to rest against 45 an upright *f* carried by the ship. These pins bearing against the upright serve to steady the apparatus in its normal position and they also act as a fulcrum to the pull exerted from the winch. The pins *c*⁴ also serve as 50 guides to the arms *c* for a short part of the descent.

The lower end *c*⁵ of each arm *c* is pivoted to a link *e*. The links *e* are pivoted at their other ends to brackets *g* fixed to the ship's 55 side. The links *e* are slightly bent at the points *e*¹ and at these points are pivoted additional links *h*. The other end of each link *h* is connected to the arm *c* by a connecting link *j* pivoted to the arm *c* at *j*¹. 60 The link *j* is preferably forked for the greater part of its length and the link *h* preferably comprises two parallel members.

Projecting from the ship's side near to the winch is preferably placed a roller or 65 pulley adapted to bear off the rope from the

ship's side when the arms are in their lower position.

When the apparatus is lowered the point at which the link *h* is pivoted to the link *j* slides down in contact with the ship's side 70 and in order that the side of the ship may not be damaged a protective plate *k* is provided. The plate *k* acts as a guide and is provided with flanges *k*¹ on each side with which the projecting ends of the pivot pin 75 of the joint fastening the members *h* and *j* together contact. As will be seen from Fig. 1 the lower parts of the flanges *k*¹ *k*¹ are broadened out so as to facilitate the entry of the sliding part. A short part of each 80 flange *k*¹ at the upper end is turned inward so as to make a three sided groove within which is guided the aforementioned pivot pin at the beginning of the downward movement, thus insuring that the said pivot pin 85 will not move away from the ship's side just at the moment of starting. This provision insures that at the start of the downward movement the links will commence to open out.

90 Below the protective plate *k* is provided a double cam *l* consisting of a plate attached to the ship's side the said cam being shaped to give the desired motion to the link *h* as it slides thereover.

95 It will be understood that the portion of the boat deck immediately under the boat is cut away so as to allow the boat to move freely into and out of the position shown at the top of Fig. 2.

100 When the boat is ready to be launched the locking clutch is released from the winch and an operator manipulates the winch brake so as to check the downward movement of the boat if desired. The weight 105 of the boat and the arms causes the arms to move downwardly as soon as the locking clutch has been released, the initial movement of the upper ends of the arms *c* being almost vertical as the pin or roller *c*⁴ slides 110 down the upright *f*.

If the pin or roller *c*⁴ were not provided the initial movement of the boat would be first in a downwardly inclined direction inboard and after a short 115 distance has been traversed the boat would take the downwardly inclined direction away from the side of the ship. This movement, however, is not desirable and the provision of the pin *c*⁴ and upright *f* renders the initial movement substantially vertical. While the pin or roller *c*⁴ bears upon the upright *f*, the weight of the boat, with the pin or roller *c*⁴ as a fulcrum, tends to 120 force the lower parts of the arms *c* outwardly thus opening out the links and at the same time the upper end of the link *h* comes 125 slightly forward and descends for a short distance within the grooves at the upper part of the plate *k* but without any serious pressure being exerted on the said plate.

This outward driving force on the lower parts of the arms *c* would be greater as the backward list of the vessel increased, (see Fig. 3), so that a ready start is insured even 5 under the most disadvantageous conditions.

- As the links begin to open out the upper end of the link *h* bears upon the plate *k* and the link *j* forces the arms *c* forward and the pin or roller *c⁴* begins to leave the upright *f*.
10 The arm *c* then continues its course downwardly supported by the links along with the winch rope, the upper end of the link *h* meanwhile sliding down the face of the plate *k* within the flanges *k¹*.

- 15 When the point *e¹* turning about the point *g* has described about three quarters of its orbit of a semi-circle, the upper end of the link *h* comes into contact with the cam *l*. The link *h* still partly slides but 20 its motion over the cam *l* is mainly a rocking motion the upper end of the link moving away from the ship's side and the lower end of the link moving down the cam *l*.

- The purpose of the cam *l* is to keep the 25 path of the boat straight and pass it smoothly into the circular part of its course. Without the cam *l* the straight part of the course taken by the boat would not be tangential to the circular part and there 30 would be a slight shock when the lower ends of the arms *c* touched the side of the ship. When the lower ends of the arms *c* come into contact with the side of the ship or with the buffers *m* which are preferably provided 35 the motion which is governed by the link work is completed. The continued motion of the apparatus is a simple turning movement about the lower ends of the arms *c*.

- 40 When the boat reaches the water it floats out of the cradle which continues to sink under the water until it reaches its lowest position. The arms are drawn up again when the boat has moved clear of the vicinity 45 of the vessel.

- Any extra boat which might be stored on the boat deck may be moved into such a position that it will be lifted by the cradle as it nears its highest position, and this second 50 boat may, in turn, be launched in the same manner.

- One method of raising the boat from the water is to provide a float attached to each arm *c* near the cradle pivots by a length of 55 line. The arms *c* are sunk below the water and the boat is maneuvered between the floats which may then be lifted into the boat, one at the stem and one at the stern. The lines to which the floats are attached 60 are drawn in and kept taut while the arms *c* are gradually raised by the winch. The boat is thus kept directly over the cradle which as it rises will lift the boat and carry it up to its original position.

- 65 In an alternative method of raising the

boat an ordinary block tackle is fastened to the extreme upper end of each arm *c* and the ropes from this tackle are passed over pulleys *n* provided at the upper end of each arm *c*. These ropes are attached to 70 a single rope which may be wound on the second barrel of the winch. A line is also attached to the beam of the cradle. The arms *c* are lowered and locked in a position some distance above the water and the cradle 75 is pulled well to one side and fastened by the line provided. The block tackle is paid out until it can be accordingly attached in the ordinary way to the boat which is then drawn up by the tackle as far as possible 80 until it is higher than the cradle. The cradle is then allowed to swing back into its vertical position and the boat is lowered into it. The power is then applied to the winch and the arms and the whole apparatus is drawn up.

The apparatus forming the subject matter of this invention has many advantages in practice as by its use the boat is placed in the water well away from the ship's side 90 and during its entire course it is positively held and cannot be thrown against the side by the rolling of the ship. Moreover, there is no tackle of any kind to unhook. As soon as the boat is borne by the water it is automatically free of every attachment to the ship. Further, the boat does not need to be moved from its normal position and there are no preliminaries to be performed before the launch, beyond the removal of the 100 boat cover. The locking clutch of the winch can be released by one man and the launch proceeds at once automatically, no power being required for launching either manually or mechanically. The apparatus is also 105 suitable for launching large rafts. The most important advantage of the apparatus, however, is the fact that a safe launch can be effected with any degree of 110 list on the launching side and with a considerable degree of list toward the opposite side.

Claims:

1. A boat-lowering apparatus comprising a cradle, a supporting arm for said cradle, 115 a downwardly movable pivotal bearing for said arm whereby the arm is adapted to gravitate under its load, and a guide and link members coöperating with said supporting arm forcing it outwardly and causing 120 it to clear the hull as it gravitates.

2. A boat-lowering apparatus comprising a cradle, a supporting arm for said cradle, a downwardly swinging pivoted lever, a pivotal bearing for the supporting arm mounted 125 on said lever whereby the arm is adapted to gravitate under its load, and a guide and link members coöperating with said supporting arm to force it outwardly during its descent.

3. A boat-lowering apparatus comprising
1 cradle, a supporting arm for said cradle,
a downwardly and outwardly swinging
5 pivotal lever, a pivotal bearing for the
supporting arm mounted on said lever where-
by the arm is adapted to gravitate under
its load, and a guide and link members co-

operating with said supporting arm to force
it outwardly during its descent.

JAMES STORIE.
